DISTILLATION OF HIGH BOILING ESTERS

Joseph E. Jewett, Larchmont, N. Y., assignor to
 American Cyanamid Company, New York, N. Y.,
 a corporation of Maine

Application April 16, 1940, Serial No. 329,849

1 Claim. (Cl. 202—52)

This invention relates to a process for distilling high-boiling organic esters, and more particularly to a process for the vacuum distillation of high-boiling esters of dicarboxylic acids.

During the distillation of high-boiling organic esters, decomposition is likely to occur as a result of heating the product to a high temperature and maintaining it at the high temperature for a prolonged period of time. To avoid this decomposition, it has been attempted in the past to apply vacuum distillation methods to processes for distilling these high-boiling esters.

The most common method of vacuum distillation, which consists of distilling material under sufficiently reduced pressure to give the required boiling point, is unsatisfactory due chiefly to overheating of the bottom portions of material caused by the hydrostatic head developed in the still. Consequent decomposition is considerable when the decomposition range lies close to the boiling point under the reduced pressure used. Another factor which greatly contributes to the decomposition of the material undergoing distillation is the necessity of maintaining the entire charge at the distillation temperature throughout the entire distillation.

Another method frequently applied provides for introduction of material into a highly heated tube of small diameter under vacuum. Evaporation takes place in the tube and the material is ejected therefrom at a high velocity by expansion of the vapor formed. It is obvious that this method is designed to avoid maintenance of the entire distilland at the distillation temperature throughout the operation. However, there are two inherent causes of overheating present in this method. First, if the length of the tube (as determined by experiment) is not just exactly right, there will be overheating of the liquid and/or superheating of the vapor. Second, fluid friction in the tube will cause a pressure drop which will, in turn, allow overheating at the feed end since the boiling point along the length of the tube varies with pressure.

According to the present invention, I have found that high-boiling organic esters may be distilled with little, if any, consequent decomposition if an excess of the material is first heated to a temperature just below the decomposition temperature and then flashed in a low pressure chamber. Undistilled material is returned, through a cooler if desired, to the charge and recirculated.

It is believed that the process of the present invention can best be understood by reference

5 to the accompanying drawing in which Fig. 1 is a diagrammatic illustration of an apparatus suitable for distilling high-boiling esters of dicarboxylic acids according to the process outlined above.

The charge of ester to be distilled is placed in tank 1 and from there is delivered to heater 6 through seal loop 5 by means of a circulating pump 3 which is driven by motor 4. The heater 10 6 is a tubular heater of conventional design heated by a medium which is introduced through pipe 27 and leaves through pipe 31.

15 After the material is heated to a temperature below that at which vaporization takes place, which temperature is regulated by the pressure existing on the system, the rate of flow, and the controller 18 which will be described in detail later, it passes through pipe 37 into flash chamber 8 where it strikes plate 38 and is spread in 20 a sheet or spray, thus affording a large area for flash evaporation. Enough vapor is evolved to cool the liquid to its boiling point under the reduced pressure existing in flash chamber 8 and the cooled material is returned through pipe 35, 25 cooler 28, the cooling medium for which enters through pipe 29 and leaves through pipe 30, and pipe 36 to seal chamber 2 from which it overflows into tank 1.

Vapors from chamber 8 pass through pipe 11 30 to condenser 12 which is fitted with cooling tubes 12a, the cooling medium for which enters through pipe 13 and leaves through pipe 14. The condensed liquid then flows through pipe 32 and seals 33 and 33a into storage tanks 34 and 34a. 35 Any uncondensed vapors leave the condenser 12 through pipe 15 to vacuum pump 16, from which they are ejected through pipe 17.

If the material being distilled is not particularly heat sensitive and not easily decomposed, 40 the cooler 28 may be eliminated, the unvaporized material then returning directly from the flash chamber 8 to tank 1. This feature of the apparatus is entirely optional and may or may not be used, depending on the material.

45 Flash chamber 8 may be fitted with fractionating plates 9 and reflux condenser coil 10 if a separation of components is desired. If this conventional fractionating device is used, separate seals and storage tanks, similar to seals 33 and 33a and 34 and 34a, are provided for each component.

50 The automatic temperature control operates as follows. Valve 41 manually controls the flow of ester to be distilled by reference to flow manometer 40, thus measuring differential pressure

on two sides of orifice 39. The boiling point of the material under reduced pressure in the flash chamber 8 is determined, and this temperature applied to one bulb 19 of a differential temperature controller 18 which holds a fixed temperature difference between bulbs 19 and 20 by throttling the heating medium passing through controller valve 21.

Increase of pressure in the flash chamber may cause the temperature determined by the absolute pressure in chamber 8 plus the set differential, which sum is the temperature on bulb 20, to go above the predetermined safe limit. In order to avoid consequent decomposition of material being distilled, the same temperature as on bulb 20 is applied to bulb 23 of an electrically operated limit controller 22 which has been set at the appropriate maximum point. The contacts of this controller 22 are opened, the coil of solenoid valve 24 is de-energized, the valve closes and air pressure from diaphragm valve 25 is cut off. The residual air in the diaphragm chamber and lines of valve 25 leaks out through small air leak 26 and valve 25 closes automatically. Thus, flow of heating medium to heater 6 is shut off, further rise in temperature in the material is prevented, and operation is suspended until abnormal conditions have passed. Means may be provided to prevent reverse operation of valve 25 until it can be reset by hand.

The above-described conventional automatic temperature controller may be omitted and if desired, the control may be manual by reference to appropriate thermometers.

The present process, since it involves a flash distillation, is more rapid than the formerly used vacuum distillation methods and this feature is an advantage of my invention.

It is another advantage of the present invention that there is no overheating of material or superheating of vapor. Only a small portion of the substance is heated to distillation temperature at one time and it is maintained at that temperature for only a very short time, i. e., a few seconds. Thus, it will be apparent that decomposition of the material is avoided or appreciably decreased.

It is a further advantage of the invention that the use of an excess of material, coupled with the return of undistilled portions for recirculation, prevents the loss of any substantial amount of material. It is thus unnecessary to maintain a high temperature for more than a very short time since undistilled material is automatically run through the apparatus again.

Another advantage of the process of the present invention becomes particularly apparent when the ester being distilled is one which is extremely easily decomposed. In such cases, it is possible to artificially cool the undistilled material, which is already somewhat cooled by the flash evaporation process, on its return to the tank. In many cases where the ester is not particularly heat sensitive, the cooling attendant upon the flash evaporation itself is sufficient to prevent substantial decomposition of the undistilled portion of the ester without any further cooling by artificial means.

The process of the present invention described above in considerable detail is applicable to all high-boiling organic esters, and particularly to high-boiling esters of dicarboxylic acids such as phthalic, maleic, succinic, and the like.

While the invention has been shown and described with particular reference to specific embodiments, it should be understood that its scope is not to be limited thereto.

I claim:

The process of distilling high-boiling esters of dicarboxylic acids which comprises heating a continuous, confined stream of the material to be distilled to a temperature below that at which decomposition takes place, rapidly vaporizing the preheated material in a flash chamber maintained under a vacuum, condensing the vaporized portion of the material, cooling the unvaporized portion sufficiently to prevent substantial decomposition of the ester, and returning the cooled unvaporized portion of the material for recirculation.

JOSEPH E. JEWETT.
